UNITED STATES PATENT OFFICE

2,608,957

WATER HEATER

Adolph A. Glawe, Green Bay, Wis.

Application November 12, 1948, Serial No. 59,703

1 Claim. (Cl. 122—165)

1. This invention relates to improvements in water heaters.

It is a general object of the present invention to provide an improved water heater which is constructed in a manner to provide an increased area of water tank surface which is exposed to the hot gases of combustion and thereby increase the efficiency of operation.

A further object of the invention is to provide a water heater which includes an inverted cone shaped inner tank portion which is so arranged that the bottom thereof is exposed to the flame of the burner so that the hot gases of combustion may travel up along the tapered tank wall.

A more specific object of the invention is to provide a water heater having an outer casing, having a tubular member spaced within said outer casing to provide an annular water chamber therebetween, and having a tank portion of inverted conical shape within said tubular member, said tank portion having means at both ends which are in communication with the annular water chamber and there being a space for hot gases located between said conical tank and tubular member.

A further object of the invention is to provide a heater of the class described wherein the efficiency of operation is increased by having an arrangement of parts wherein the hot gases of combustion wipe both the outer surface of the conical inner tank and the inner surface of the annular water chamber, said hot gases also directly contacting conduits which lead from the water chamber to the lower portion of the conical inner tank.

A further object of the invention is to provide a heater of the class described having valve means for temporarily shutting off communication between the lower ends of the inner and outer tanks to thereby selectively provide for quick heating of the water in the inner tank.

A further object of the invention is to provide a water heater of the class described which may be used successfully with any type of conventional heating unit whether utilizing oil, coal or gas.

A further object of the invention is to provide an improved water heater of the class described which is strong and durable, which is relatively easy to manufacture, which is economical to operate, and which is otherwise well adapted for the purposes described.

With the above and other objects in view the invention consists of the improved water heater, and all of its parts and combinations, as set forth in the claim, and all equivalents thereof.

In the drawings accompanying and forming a

part of this specification, wherein is shown one complete embodiment of the preferred form of the invention, and wherein the same reference characters indicate the same parts in all of the views:

Fig. 1 is a vertical sectional view of the improved water heater;

Fig. 2 is a transverse sectional view taken approximately along the line 2—2 of Fig. 1; and

Fig. 3 is a transverse sectional view taken approximately along the line 3—3 of Fig. 1.

Referring more particularly to the drawing, the improved water heater has an elongated outer cylindrical shell or casing 5 having its upper end closed by a circular plate 6. Positioned within and substantially concentric with the outer shell 5 is an inner cylindrical tube 7 which is formed at its lower end with an outwardly projecting annular flange 8. The peripheral edge of the flange 8 is sealingly connected in any suitable manner to the inner surface of the shell 5. The flange 8 of the inner shell 7 may be positioned on a supporting angle 9 extending around and fixed to the inner surface of the shell 5 as shown. Any suitable means may however be used to close the bottom of the annular water chamber formed between the shell 5 and tube 7.

An inverted conical tank 10 is positioned within the inner tube 7 and is preferably concentric therewith. The upper marginal edges of the conical tank 10 and of the inner shell 7 are sealingly connected as at 11, and the lower tip of the conical tank 10 is preferably rounded as at 12. Extending diametrically outwardly and downwardly from the lower end of the conical tank 10 are conduits 13 and 14. Any desired number may be employed. The conduits 13 and 14 provide communication between the interior of the tank 10 and the annular space 15.

Extending diametrically across the conical tank 10 near its upper end and opening through opposite side wall portions thereof is a transverse flue or conduit 16. Projecting upwardly from a central portion of the flue portion 16 and extending through the top plate 6 is a vertical flue portion 17. Extending vertically through the top plate 6 is a hot water outlet pipe 18. Opening into the space 15 through the outer shell 5 and adjacent the lower end of the inner shell 7 is a cold water inlet pipe 19.

Supported in any suitable manner below and concentric with the conical tank 10 is a heating unit 20. A pot type oil burning unit 20 is shown, but it is obvious that any suitable type of unit may be used, regardless of the type of fuel. As shown in Fig. 1, the burner 20 is provided with a pair of oppositely extending ears 21. The

burner 20 is removably supported by means of bolts 22 secured to the under side of the annular flange 8, and extending through the ears 21, wing nuts 23 being threaded on said bolts under the ears 21. An oil line 24 is provided to deliver fuel to the burner 20. In order that sufficient air be provided to support combustion in the burner, the lower end of the shell 5 is formed with suitable ventilating means, such as the apertures 25.

Mounted on and extending through the outer shell 5 opposite the outer ends of the conduits 13 and 14 are a pair of valves 26 and 27 respectively. The valves 26 and 27 have externally accessible manually engageable hand wheels 28 and 29 and valve members 30 and 31 respectively. When the hand wheels 28 and 29 are turned inwardly the valve members 30 and 31 move inwardly therewith, to the dot and dash line positions shown, to seal off the outer ends of the conduits 13 and 14. Threaded into an aperture in the top plate 6 is a vent plug 32.

In operation, the improved heater may be filled by introducing water through the inlet conduit 19. During the filling operation the air displaced by the water may be vented by temporarily removing the plug 32. When the heater is full, the space 15 between the inner shell 7 and the outer shell 5 is filled with water, as are the conduits 13 and 14 and the conical tank 10. Upon lighting the burner 20, a flame is emitted from the top thereof. The lower end of the conical tank 10 spreads this flame outwardly so that as the gases of combustion rise around the tank 10, at the same time these gases wipe the inner surface of the inner shell 7. The spent gases of combustion travel out through the flues 16 and 17.

Since the conical tank 10 has a volume which is less than that of the space 15, and since the lower end of the tank 10 comes in contact with the hottest portion of the flame from the burner 20, the water in the tank 10 is heated first. As the water in the tank 10 is thus heated, it rises, causing cooler water to flow in through the conduits 13 and 14 to displace the heated water which has risen. The circulation of the water thus set up by the rising currents in the tank 10 is indicated by the arrows in Fig. 1. It causes the cooler water to flow downwardly between the shells 5 and 7 as shown. This circulation will continue as long as heat is supplied by the burner. The heated water may be drawn off through the conduit 18.

When it is desired to produce hot water in a minimum of time, the outer ends of the conduits 13 and 14 are closed by turning the hand wheels 28 and 29 until the valve members 30 and 31 are in the dot and dash line position of Fig. 1. This prevents cool water from entering the tank 10 through the conduits 13 and 14, and as a result, the water in the conical tank 10 heats up quickly because of its exposure to high burner temperatures and because of the relatively high ratio of heating surface to contained volume thereof. For safety purposes a suitable pressure relief valve (not shown) may be used in the system to avoid the dangers presented by genera-

tion of steam within the improved heater, should the valves 26 and 27 be inadvertently left closed for too long a period with the burner in operation. Opening the valves 26 and 27 permits the normal circulation of the water as described hereinbefore.

The improved construction, by reason of the incorporation therein of the novel conical inner tank, provides an efficiency hitherto unobtainable in single flue water heaters. This heater can be easily and inexpensively manufactured from a minimum of parts, and it is particularly well adapted to mass production methods.

Various changes and modifications may be made without departing from the spirit of the invention, and all of such changes are contemplated as will come within the scope of the claim.

What I claim is:

20 In a water heater, an outer casing; a smooth surfaced tubular inner shell within said outer casing and spaced therefrom to form an annular water chamber, means for closing the bottom of said water chamber; a smooth surfaced inverted conical tank of not substantially less length than 25 said inner shell positioned within said inner shell to form a combustion chamber of decreasing cross-section from bottom to top, there being communication between said conical tank and said water chamber at the upper ends thereof; a 30 plurality of conduits, within the combustion chamber formed by said conical tank and said inner shell, connecting a lower end portion of said conical tank with a lower end portion of said water chamber; a valve member in said annular 35 water chamber for each conduit positioned to selectively close the adjacent end of said conduit to prevent the flow of water therethrough, said valve members each having an externally accessible manually operable stem which projects through the outer casing; a flue extending into said combustion chamber through said conical tank, all portions of said flue being substantially above the horizontal outer line of the conical tank; a cold water inlet conduit entering a lower end portion of said outer casing; and a hot water conduit extending through said outer casing and having its inner end positioned above said conical tank, said outlet conduit being at all times in direct communication with the interior of said conical tank and with said annular water chamber.

ADOLPH A. GLAWE.
